UNITED STATES PATENT OFFICE.

MARSENA R. JULIAN, OF BIRMINGHAM, ALABAMA.

BLOCK-SIGNAL SYSTEM.

1,243,419.

Specification of Letters Patent. Patented Oct. 16, 1917.

Application filed July 31, 1914. Serial No. 854,393.

To all whom it may concern:

Be it known that I, MARSENA R. JULIAN, citizen of the United States, residing at Birmingham, in the county of Jefferson and State of Alabama, have invented certain new and useful Improvements in Block-Signal Systems, of which the following is a specification.

My invention relates to block signal systems and particularly to a block controlled cab signal system. With the ordinary block signal systems at present in use on practically all roads there is no way to prevent an engineer from running his train by any signal which may be set against him and no way to positively compel the engineer to reduce the speed of his train upon receiving either a cautionary signal or a danger signal. Sometimes the engineer runs his train past a signal set against him out of sheer carelessness or the desire to make up time, and on other occasions he runs it by the signal because he is unable to see it, as in case of heavy snow or fog.

It has been proposed to display the proper signals within the cab of a locomotive so that the engineer cannot possibly fail to see the signals, but here again discretion is left with the engineer to run the train by the signals or to pay no attention to them if he so desires. This has led to many accidents and is a constant source of danger. Even where the engineer obeys the signals there is still another element of danger in the engineer maintaining too high a train speed either along a normally perfectly safe portion of the track or in some particular section in his desire to make up for lost time, and as far as I know, no means has, so far, been provided which will automatically limit the maximum speed of the train or automatically bring the train either to a moderate speed in case of a cautionary signal being set against the train or bring the train to a stop in case a danger signal is set against the train.

The primary object of my invention is to provide means for automatically controlling the speed of trains in a block signal system and in this connection to provide means whereby in the first place the train cannot be run faster than at a predetermined speed, even with a clear track. In the second place that when the engineer receives a cautionary signal due to the presence of a train within a predetermined num-

ber of blocks ahead the speed of the following train shall be automatically cut down to a predetermined degree, and in the third place that when the train receives a danger signal due to the presence of a train within a dangerous distance the speed shall be automatically cut down to a minimum.

Another object of my invention is to so construct the mechanism that the automatic service application of the brakes shall not in any way interfere with the regular or usual application of the brakes by the engineer and further, to so construct the mechanism that the engineer cannot possibly prevent the automatic application of the brakes, as above stated.

Another object of the invention is to provide a train controlled and cab signal mechanism wherein on entering a block a "test" is made to show that the track wiring and wiring of the cab signal mechanism are in proper working condition and such that if they are not in proper working condition an application of the brakes shall immediately be made.

Still another object is to so construct my improved train control and signal mechanism that on entering a block a "danger" application of the brakes shall be made unless a clear signal or a cautionary signal is immediately received.

Another object is to so construct the signal mechanism that in addition to automatically controlling the speed of the train, signals shall be displayed within the cab of the engine whereby the engineer may readily determine whether he is running his train under a clear signal, a cautionary signal or a danger signal and provision shall be made for the application of the brakes and a characteristic signal if by any chance the signaling mechanism is out of order and does not properly work.

Still another object is to so construct the mechanism that a break of any wire of the cab signal system except the clear signal wire, will cause the brakes to be applied and, in this connection, to provide a mechanism wherein if the clear signal wire breaks, while the brakes will not be applied immediately, yet the brakes will be applied at the entrance end of the next block.

A further object in this connection is to provide means whereby after the clear signal wire breaks and the brakes are applied, the engineer may release the brakes and per-

mit the train to go forward but not beyond a very low speed.

Still another object is to provide a cab signal mechanism in which there shall be at least two elements which must fail in order to permit a train to enter a block already occupied by a train.

Another object is to so construct the cab signal mechanism that if the wires leading from the "test" caution or danger contacts or shoes should break, the clear signal light would immediately go out and the brakes be immediately applied and remain applied until the break or interruption in the broken wire is mended or until the engineer can cut out the signal mechanism, and in this connection to provide means whereby if the wire leading from the clear signal shoe or contact should be grounded the brakes will be applied.

Still another object is to provide a closed circuit cab signaling system in which a break or ground will cause a danger application of the brakes, and thus, bring the train to a stop, until repairs are made.

A further object is to provide means whereby a signal of some sort whether clear, cautionary, or danger, will always be received at the entrance end of each block, and the failure to receive a proper signal will automatically cause an application of the brakes.

Still another object is to provide a mechanism whereby the brakes will be immediately and automatically applied but whereby the engineer can immediately throw off the brakes provided the speed of the train is within the limit set for danger, this mechanism acting, however, if the speed is too high to prevent the release of the brakes, and to this end to provide two circuit closers necessary to be closed in order to permit the release of the brakes, one circuit closer acting automatically and being dependent upon the speed of the train and the other being manually actuatable.

Still another object is to provide means whereby if a danger signal is received on entering a block, the train will be brought to a sudden stop unless the engineer immediately closes the circuit, and whereby this closing of the circuit will release the brakes but will not permit the speed to be increased beyond five miles an hour or some other predetermined rate, and whereby, if on entering a second block the train shall receive a danger signal, the train will be again brought to a full stop unless the engineer immediately closes said circuit.

Still another object is to provide a mechanism wherein, if a cautionary signal is received and if the train is running at a cautionary speed, that is, within a certain limit of speed, the cautionary signal will show, and brakes will be applied if the engineer does

not close a certain circuit, but, wherein, if the engineer closes this circuit when the train is running at cautionary speed, the brakes shall not be applied. If, however, the speed of the train is above what may be termed "cautionary" speed, then the brakes are not released until the speed of the train is reduced to a safe and predetermined degree.

Other objects will appear in the course of the following description.

My invention is illustrated in the accompanying drawings, wherein:

Figure 1 is a diagrammatic view of my cab signal mechanism.

Fig. 2 is a perspective view of the automatic circuit making and breaking mechanism.

Fig. 3 is a side elevation of the construction, the outer casing and frame being in section on the line 3-3 of Fig. 4.

Fig. 4 is a view on the line 4-4 of Fig. 3.

Fig. 5 is a section on the line 5-5 of Fig. 4.

Fig. 6 is a perspective view of certain detents and their co-acting armature.

Fig. 7 is a detailed view partially in section, of the vent valve and its controlling magnet.

Fig. 8 is a longitudinal vertical sectional view of one of the track contact switches;

Fig. 9 is a horizontal sectional view of the same;

Fig. 10 is a diagrammatic view of a track wiring system with which my signal system may be employed.

Corresponding and like parts are referred to in the following description and indicated in all the views of the accompanying drawings by the same reference characters.

Referring to the diagrammatic view of Fig. 1, *x-x* designates the rails of a track and *X* a truck representative of and standing for a vehicle such as a locomotive, tender or car traveling on the rails. Carried by the truck are the four shoes, *a*, *b*, *c* and *d*. These letters designate, respectively, the "test" shoe, the "clear" shoe, the "caution" shoe and the "danger" shoe. These shoes are adapted to contact with the track contact switches one of which is illustrated in Fig. 8. These contact switches are fully described and claimed in my prior application, Serial No. 758,452, filed on the 2nd day of April, 1913.

The test contact switch *A* is grounded directly to the track rails while the caution, clear and danger contact switches are connected to the blocks ahead, as will be later described, in such manner that the danger and caution contact switches are grounded if a train is on the next block ahead and the clear contact switch is grounded if no train is within a predetermined distance.

Mounted in the cab of the engine are four

slides, 1, 2, 3 and 4. These slides are vertically arranged and are disposed in a suitable frame, as will be later described and shown in Fig. 2. The slide 1 is urged downward by a spring 5 but is normally held in a raised position by a latch or pawl 6. The slide 1 has a prolongation 7, which engages an outstanding lug 8 on the slide 2. This slide is normally held up by a spring 9 but when it is depressed, as by a depression of slide 1, it is held depressed by a latch or bolt 10.

The slide 4 is normally held raised, against the force of a spring 11 by a latch 12. The slide 3 is normally held raised by a spring 13, but when depressed is held depressed by a latch 14. The slide 3 has an extension 15 which is engaged by the slide 4 in its downward movement so that a depression of the slide 4 depresses slide 3 in the same manner as a depression of the slide 1 depresses the slide 2. Slide 3 has an extension 16 the upper end of which is provided with a nose 17 engageable with a beveled faced lug 10^a on the latch 10 upon a depression of the slide 3. Thus if the slide 2 is depressed and held by the latch 10 then a depression of the slide 3 will cause the nose 17 to engage a lug projecting from the face of the latch 10 and cause the latch to lift, permitting the slide 2 to be drawn upward.

The slide 1 carries a projecting contact member 19 which is insulated from the body of the slide. The slide 4 also carries a projecting contact member 20 also insulated from the body of the slide. The slide 3 has a projecting contact member 21 insulated from the body of the slide and having two oppositely projecting tapered faces. The slide 2 has a projecting contact member 22 which, however, is not insulated from the body of the slide. This contact member has oppositely disposed beveled contact faces.

Each of the several latches 6, 10, 12 and 14 is controlled by a corresponding electromagnet, which when energized withdraws the latch from its engagement with the slide. All of the latches are forced into engagement with the several slides by being resilient. In other words they are spring-actuated latches.

The magnet controlling the latch 6 is designated 23; the magnet controlling the latch 12 is designated 24. The magnet controlling the latch 10 is numbered 25 and the magnet controlling the latch 14 is designated 26.

The contact member 19 carried by the slide 1 normally electrically engages with contact fingers 27 and 28, one of which is connected by a wire 29 to the point 30^a of a one-point relay magnet 30 which normally has contact with the terminal of a wire 31 which passes through an electromagnet 32 and then to a ground 33. The magnet 32

controls a vent-valve which when open permits the escape of air from the brake pipe of an air brake system and when closed prevents the escape of such air. When the vent-valve is opened the pressure in the brake pipe of the air brake system will be reduced, and this will cause the brakes to be applied in the usual manner.

From the contact finger 27 extends a wire 34 to a contact finger 35 which normally has electrical engagement with the contact member 20. Also normally in engagement with the member 20 is a finger 36 from which a wire 37 extends to a generator G, the other side of which is grounded at 38. While I prefer to use a generator, any other source of electrical energy, as for instance, a storage battery may be used. It will thus be seen that normally current flows from the generator through the magnet 32, energizing this magnet and holding the vent valve closed. When the circuit is broken either by a depression of the slides 1 or 4, or by the deenergizing of magnet 30, the magnet 32 will be deenergized which will cause the opening of the vent valve, as will be later stated, and the application of the brakes.

The magnet 30 on one side is connected to a ground 39 and on the other to a wire 40 which has three stepped terminals 40^a, 40^b and 40^c. Co-acting with these terminals are the contact points 41^a, 41^b and 41^c. These are arranged to be shifted in the order named by a speed controlled centrifugal governor 42. This may be of any suitable type. As shown, however, rotation is communicated to the shaft of the governor from the train by any suitable means and as the speed of the train increases the governor balls will be thrown outward by centrifugal action. This will raise a rod 43 and as the rod rises it will first lift the contact point or switch 41^a from contact with the terminal 40^a. After the point 41^a has risen a certain distance it will operatively engage the point 41^b which will be lifted from contact with the point 40^b. After this is raised a predetermined distance it will operatively engage the point 41^c lifting it from its engagement with the point 40^c.

The point 41^a is connected by a wire 44 to a contact finger 45 insulated from but disposed adjacent to the finger 46 from which extends a wire 47 to a danger signal which, as illustrated, has the form of a red electric lamp 48, this lamp being connected to a ground 49. The slide 2 is electrically connected, as will be later stated, with the generator and hence, when the slide 2 is depressed, current will flow from the generator through the slide and, dividing at the contact fingers 45 and 46, will pass to the lamp 48 and ground and, by way of wire 44 to the contact 41^a and thus through the magnet 30.

Normally the slide 2 is raised and current passes by way of the slide 2 to the slide 3, from the contact finger 50 and the wire 51 to the contact member 21 on the slide 3. 5 When the slide 3 is raised, that is, when the slide 3 is in its normal position the contact member 21 engages the pair of fingers 52 and 53 which are insulated from each other. From the finger 53 a wire 54 leads to the white light 55 and so to the common ground 49. From finger 52 a wire 56 leads to the point 41^c.

Thus, when the slides 2 and 3 are in the position shown in Fig. 1, current will pass from the generator to the slide 2, thence by way of the finger 50 to the contact member 21 and then, dividing at this point the current will pass to the white light to and through the magnet 30 energizing this magnet. When the slide 3 is depressed the contact member 21 electrically engages the spaced fingers 57 and 58. From 58 a wire 59 leads through a green signal lamp 59^a to the ground 49 and from the finger 57, a wire 60 leads to the point 41^b and thence to the ground 39.

It will be seen that it will require only a rise of train speed above a relatively low degree to lift the contact point 41^a and break the circuit through the wire 44 to the magnet 30. It will also be seen that a greater rise of speed will lift the point 41^b and break the circuit through the wire 60 to the magnet 30 and that it will require a still greater rise of train speed to lift the contact point 41^c and break the circuit through the wire 56 to the magnet 30. The governor may be arranged to break these circuits at any desired rate of speed, but it may be assumed that a speed of under five miles an hour will not cause lifting of the point 41^a but that a speed of over five miles an hour will lift the point 41^a. A speed of under twenty miles an hour will not lift the point 41^b but when the train is running over twenty miles an hour the point 41^b will be lifted. A speed of over fifty miles an hour will lift the point 41^c.

When the train is running under a clear signal the parts will have the position shown in Fig. 1. The point 41^c will be active, that is, current will pass from the generator through the point 41^c to the magnet 30, but the points 41^a and 41^b will be inactive. If at this time the speed of the train is above fifty miles an hour, assuming fifty miles an hour for the maximum speed allowed, then all the contact points will be lifted, including the point 41^c and the magnet 30 will be de-energized, breaking the circuit through the magnet 32 at the point 30^a and the brakes will be applied until the speed of the train slackens to or below the maximum speed indicated. When a cautionary signal is received, as will presently appear, the points

41^a and 41^c will be rendered inactive and the point 41^b active hence, if the train is running at more than twenty miles an hour when the cautionary signal is received, or should attempt be made to run at a speed higher than twenty miles an hour under a cautionary signal, the point 41^b will be lifted (the point 41^a being also lifted) and the circuit will be broken through the magnet 30, causing an application of the brakes until the speed of the train is reduced to twenty miles an hour or below. When a danger signal is received the points 41^b and 41^c are rendered inactive and the point 41^a active and if, when the train is running under a danger signal the speed is higher than a minimum of say, five miles an hour, the circuit will be broken through the wire 44 from the generator, then the magnet 30 will be de-energized and the brakes will be applied until such time as the speed of the train is reduced to five miles an hour or less.

Extending from the shoe *b* or the clear signal shoe is a wire 61 which passes through the coils of a two-point magnet 62, thence to and through the magnet 25 (which controls the latch 10), thence to and through magnet 26, (which controls the latch 14), thence to the generator by wire 37. From the wire 37 extends a wire 64 which passes through the magnet 23 and thence extends to the danger shoe *d*.

From the cautionary shoe *c* extends a wire 65 which passes through the magnet 24 and thence extends by the wire 37 to the generator.

From the test shoe *a* extends a wire 66 which passes through a two-point relay magnet 67 and then extends to the wire 29 by which it is connected through the points 28 and 27, 35 and 36 to the generator.

From the cautionary shoe *c* extends a wire 68 which passes through the one-point relay magnet 69 to a ground 70 and from the danger shoe *d* extends the wire 71 through the one-point relay magnet 72 to the ground 70. Both of the magnets 69 and 72 are high resistance magnets to prevent energization of low resistance magnets in the same circuit.

From the wire 66 extends a wire 73 having a terminal normally in contact with the point 62^a of the relay 62. This point 62^a is in turn connected by a wire 74 to a point 67^a which is normally out of electrical contact with the ground 75.

From the test shoe *a* extends a wire 76 which is connected to a point 62^b which is normally in contact with the terminal of a wire 77 leading to the point 67^b of the two-point relay 67. This point 67^b is normally in contact with the terminal of a wire 78 leading to a point 72^a of the relay magnet 72. This point is normally in contact with the terminal of a wire 79 leading to the point 130

69^a, which is normally in engagement with the terminal of a wire 80 which leads to the slide 2.

The slide 2 under normal circumstances 5 is connected to the generator by a wire 80, point 69^a, wire 79, point 72^a, wire 78, point 67^b, wire 77, point 62^b, wire 76, shoe *a*, wire 66, wire 29, fingers 27 and 28, wire 34, fingers 35 and 36 and wire 37.

10 Thus, in the normal position of the parts 15 current is passing through the white light and through the magnet 30 and through the magnet 32. It should be noted at this point that the relay magnet 67 is so wound that under normal conditions it will not attract its armature, due to the resistance of the relay 30 and the signal light in the same circuit. If, now, however, the speed of the train increases beyond the maximum, as for 20 instance fifty miles, the circuit through the wire 40 will be broken, deenergizing the magnet 30 and breaking the circuit through the magnet 32 which will cause a service reduction of the brake system and cause an 25 application of the brakes until such time as the speed drops to fifty miles an hour, whereupon the circuit is again completed and the vent-valve is closed.

30 The operation of the instrumentalities above set forth, is as follows:—

Upon entering a block, the train being assumed to move in the direction of the arrow, Fig. 1, the first contact switch met with would be the "test" contact switch A. 35 This test contact switch is always grounded to the rails of the track. Therefore, the test shoe *a*, is grounded when it engages the contact switch. When so grounded, the circuit is completed from the generator G 40 through the wire 37, the contact finger 36, the contact member 20 of the slide 4, the contact finger 35, the wire 34, the contact finger 27, the contact member 19 of the slide 1, the contact finger 28, the wire 66 45 and electro-magnet 67 therein, the test shoe *a* and the test contact switch A, energizing the magnet 67. This causes the point 67^a to engage the wire leading to the ground 75 and makes a "stick" relay or holding relay 50 of the relay magnet 67.

The energizing of the magnet 67 causes the point 67^b to break the circuit through the wires 78 and 80 to the slide 2, and thus cuts off the supply of energy to all of the 55 lamps and to the magnet 30. The cutting off of the energy to the magnet 30 would cause the application of the brakes were a new signal not immediately received. In actual practice, however, this breaking of 60 the circuit through the slide 2 just causes the white light to flicker and causes an opening and closing of the vent-valve and no actual application of the brakes is made by this "test" unless no other signal is immediately received. If something be wrong

and no other signal is received then the lights will remain out and the brakes will be applied. Disposed within the wire 66 between the relay 67 and the wire 73 is a manually operable, normally closed switch 70 66'. If after receipt of a test signal no other signal is received, the relay magnet 67 may have its ground broken by opening the switch 66' so that the engineer may start the train and proceed with due care 75 until the next test occurs. No other signal will be received if the signal circuits are deranged. The receipt of a signal, however, reestablishes the connection between the slide 2 and the generator.

80 Now if there is no train on the block ahead the clear signal shoe will be grounded when it is engaged with the clear signal contact switch B. Upon such engagement a circuit is completed from the generator 85 through the magnets 62, 25 and 26. The energizing of the magnet 62 causes the point 62^a to break the circuit through the magnet 67 causing the deenergization of this magnet and the point 67^b will immediately close the circuit at this point from the generator to the slide 2 and thence to the lights. This, however, only partially completes the circuit.

90 While the shoe *b* is in contact with the contact switch B the circuit will be broken through the point 62^b, but closed through the point 67^b. When the shoe *b* leaves the contact switch, however, the circuit is again closed through the point 62^a. The object of this is to protect the device from grounding. 100 If the clear contact shoe should become grounded it opens the point 62^b and breaks the circuit through the lights and the controlling magnet 30.

105 The energizing of the magnets 25 and 26 will cause oscillation of the latches 10 and 14 but will cause no change in the slides 2 and 3, both of these slides being held in their raised position by the springs 110 connected thereto. It will be seen that when the circuit is completed from the generator to the slide 2 by breaking the contact of the shoe *b* with the grounded contact switch B, a circuit will be completed from the generator through the white light 115 55 causing this white light to burn and a circuit will also be completed through the magnet 30 by way of the point 41^c provided the train is running at a speed not greater 120 than the maximum speed allowed by the governor.

125 If the train be running on a perfectly clear track, therefore, the white light continues to burn and the only change will occur on entering a block where the engagement of the test shoe with the test contact switch will cause a flicker of this white light. If the block ahead is clear, however, this white light will continue to burn. If 130

6 after receiving the test signal the shoe *c* is grounded by its engagement with the contact switch *C* which has been previously grounded by the presence of a train a pre-
 5 determined number of blocks ahead, then the magnet 24 is energized. This withdraws the latch 12, allowing the spring 11 to draw the slide 4 downward and this draws downward on the slide 3. The down-
 10 ward movement of the slide 4 breaks the circuit from the generator to the valve controlling magnet 32, which causes an application of the brakes. The downward movement of the slide 4 carries with it the slide 3, as previously stated, which breaks the circuit through the white light and through the point 41^a, and establishes a circuit through the green light 59 and through the point 41^b to the magnet 30. If at the time
 15 20 the cautionary signal is received the engineer is running his train at a speed not greater than twenty miles an hour, (assuming this to be the maximum speed allowed for running under a cautionary signal) the
 25 engineer can release the brakes by mechanism which will be later stated and which is shown in Fig. 2, this mechanism operating to lift the slide 4. It cannot, however, operate to lift the slide 3 as this slide is
 30 held downward by the engagement of the nose 18 with the lug 10^a of the latch 10. This manual lifting of the slide 4 will again close the circuit from the generator through the magnets 32, provided the train is running at the cautionary speed of under twenty miles an hour. If, however, the train is running above the cautionary speed of twenty miles an hour, the lifting of the slide 4 by hand and the closing of the circuit through the magnet 32, then the fingers 35 and 36 will not affect the energizing of the magnet 32, for the reason that the circuit will be broken between the point 41^b through the magnet 30 and, therefore, the
 40 45 point 30^a will be out of contact with the terminal of the wire 31. It will thus be noted that there are two places where the circuit through the magnet 32 will be broken. One of these breaks may be closed
 50 55 by hand but the other is closed only if the speed is within the maximum limit set for running under the particular signal which is displayed.
 If, after the test has been received, the danger shoe *d* upon its engagement with the danger contact switch *D* is grounded by the previous grounding of the contact switch *D*, then a circuit is completed from the generator by way of the wire 63-64 through
 60 65 the magnet 23 to the danger contact shoe and thence to the ground. The energizing of the magnet 23 withdraws the latch 6 from its engagement with the slide 1 and the spring 5 causes the slide 1 to drop, carrying with it the slide 2. When the slide 2

drops the latch 10 engages in a notch in the slide and thus holds the slide 2 lowered until another signal is received. The dropping of the slide 1 breaks the circuit from the generator through the contact fingers 27 and 28 to and through the magnet 32 which causes the application of the brakes. The drawing down of the slide 2 breaks a circuit from the generator through either the cautionary or the clear light, which ever happens to be burning, and establishes a circuit between the generator and the red lamp 48 and between the generator and the point 41^a and from thence by way of the wire 40 to and through the magnet 30. It will thus be seen that a circuit through the red signal light is established and that a circuit through the valve controlling magnet 32 is broken so that a danger application of the brakes is secured, and the danger signal displayed. If the speed of the engine when the danger signal is received is above the minimum prescribed for running under a danger signal, as for instance, above five miles an hour, the point 41^a will have been raised so that the circuit through the magnet 30 is broken, thus releasing the point 30^a and breaking a circuit through the magnet 32. If, however, the train, when it receives its danger signal is running at a speed below five miles an hour or any predetermined minimum speed, then the circuit will only be broken at the gap between 27 and 28 and will not be broken by the point 30^a. Under these circumstances the slide 1 may be again raised to close the circuit through the magnet 32 by manual actuation, as will be later described and the brakes may be released. Thus it will be seen that the brakes while applied automatically upon the receipt of a danger signal may be released by the engineer provided the train is running at a speed less than five miles an hour, but that if the train is running at a speed greater than five miles an hour the engineer cannot prevent the application of the brakes or release the brakes until the speed has been reduced below five miles an hour.
 The train will continue to run under a danger signal and at a predetermined slow speed until the next block is reached. If here a clear signal is received the magnets 25 and 26 will be energized. The energizing of magnets 26 will merely reciprocate the latch 14 but the energizing of magnet 25 will cause the withdrawal of latch 10 from its engagement with the slide 2 and the spring 9 will cause the slide to rise, thus breaking the circuit through the red light and through the point 41^a, and completing a circuit through the white light and through the point 41^b. It will be understood that if here a cautionary or danger signal is received the engineer manually returns the slides 1 and 4

115 120 125 130 135

to their normal positions by means which will be later described. This will suffice to prevent the application of the brakes provided the train is not running over either the cautionary speed limit or the danger speed limit.

In Figs. 2, 3, 5 and 6 I show the controlling mechanism comprising the slides 1, 2, 3 and 4 and the magnets 23, 24, 25 and 26 as actually arranged in practical use. In these figures, 81 is a base supporting an end-piece 82. The slides 1, 2, 3 and 4 are supported in the frame 83 comprising an inverted U-shaped strip attached to the base. 15 To the legs of this strip is attached a transverse extending strip 84. The slides are supported for vertical movement in guide rods 85 which pass through the strips 83 and 84, as shown plainly in Fig. 2.

20 Also mounted on the base is the supporting member or bracket 86 supporting the contact fingers 52 and 53. There are certain differences between the diagrammatic view of this mechanism in Fig. 1 and the construction as actually used and shown in the remaining figures. These differences do not in any way affect the operation of the mechanism but in the diagram it is found necessary to distort the actual shape of the slides 25 in order to make the drawings and operation clear and, thus, while in the diagrammatic view there is shown two magnets 25 and 26 one governing the latch 10 and the other governing the latch 14, in reality there 30 is only one magnet used and this magnet in Figs. 2, 3 etc., is designated 25 and 26.

In Fig. 1 again the latches 10 and 14 are shown as disposed one below the other while as a matter of fact the latches are disposed 40 side by side, as shown clearly in Fig. 6, the latches being of spring metal and having their lower ends bent outward and notched as at 10^b and 14^b. The armature 87 of the magnet 25 and 26 is connected to these 45 spring pawls or latches 10—14 by means of an angular member 88 which is fastened to the armature and which has a lug 89 extending into the notches 10^b and 14^b whereas in the diagrammatic view the latches 10 and 50 14 are shown as provided with outwardly projecting lugs, one of which is designated 10^a. As a matter of fact these lugs are constituted in the working embodiment of my invention by the inwardly turned extremities of the spring pawls or latches, these inwardly turned extremities being lettered, therefore 10^a and 14^a.

In Fig. 1 the slide 3 is shown as provided with an upward prolongation 16 which is 60 adapted to engage with the lug 10^a and the slide 2 is provided with the downwardly extending prolongation in Fig. 1 adapted to contact with the lug 14^a. In actual construction the edge of the slides 2 and 3 are 65 provided with notches which engage the ex-

tremities of the pawls 10 and 14 and also provided with inwardly extending thickened lugs which are adapted to engage with the outwardly projecting lip 89 and member 88 so that when either one of the slides is depressed it will act to release the corresponding pawl from the other slide so as to permit that slide to rise. These inwardly extending thickened portions have, therefore 70 been designated 16^a and 16^b.

75 It will be noted from Fig. 4 that all of the slides 1, 2, 3 and 4 are angularly bent at their extremities and it is through these extremities that the guide rods 85 pass.

The means whereby the slides 1 and 4 are 80 manually raised after a depression caused by the receipt of a cautionary or danger signal comprises a lever 90 which is formed to provide the opposed legs 91 and 92 which are pivoted to the downwardly extending 85 legs of the strip 86. The forward leg 91 is angularly bent as at 93 so as to engage beneath the projecting contact member 19 of the slide 1 while the leg 92 is also angularly bent at its extremity so as to engage beneath the projecting contact member 20. A spring 94 acts to hold the lever in the position shown in Fig. 2. When the lever is 90 depressed either one of the slides 1 or 4 which happens to be dropped will be raised to its normal position against the force of the springs which act to draw the slides downward.

The mechanism shown in Fig. 2 is intended to be inclosed within a casing 95 through which projects the extremity of the lever 90, this lever being connected to any suitable actuating rod or cord 96.

In Fig. 7 I show a detailed view of the vent-valve and the armature magnets 32, 100 whereby the vent-valve is operated. In this figure 97 designates the supporting frame which carries the magnets 32. Slidably mounted on this frame is the armature 98. The upper portion of the frame 97 is formed 105 with a valve casing 99 having a valve seat 100 and a vent 101 co-acting with the valve-seat 100 and operating within the casing 99 is a valve 102, this valve having a reduced portion 103 which is adapted when the 110 valve is open to register with the vent 101. The valve casing 99 has extended from it a duct 104 which connects to the equalizing reservoir of an air brake system, not shown. When the valve is dropped, communication 115 will be established between the vent 101 and the duct 103 causing a venting of the equalizing reservoir. The valve 102 is mounted upon a stem 105 the lower end of which is nicked as at 106. Surrounding this stem but spaced therefrom is a sleeve 107. Attached to the armature 98 is a sleeve 108 which surrounds the stem 105 which is attached to the armature and which is internally screw threaded at its lower end. 120 125 130

Disposed in this screw threaded end of the sleeve is an adjusting screw 109 having a head 110 and a stem 111 which at its end engages the end of the valve stem.

- 6 It will be obvious now that when the magnets 32 are energized the armature 98 will be drawn up against the magnets and the valve 102 will be held to its seat. When, however, the magnets are deenergized the 10 armature and the valve are dropped. By rotating the adjusting screw 109 the valve may be forced upward or allowed to move downward and thus so adjusted that it will engage its seat just before the armature 98 15 engages the poles of the magnets. Furthermore, by this construction the valve may be rotated by the insertion of an implement into the nick 106 so as to cause its face to ground upon the face of the valve seat and 20 thus secure a thoroughly tight joint between the face of the valve and the face of the valve seat.

The form of contact switch used by me is shown, described and claimed in my prior 25 application for patent, Serial No. 758,453, filed on the 2nd day of April, 1913, and forms no part of my present invention. In order to illustrate my present invention, however, this form of contact switch is 30 shown in Figs. 8 and 9. It comprises a casing 112 mounted upon the ties beside the track. Passing through this casing is a rock-shaft 113 from which projects an arm 114 connected to a spring 115 which resists 35 any movement of the rock-shaft in either direction but, of course, yields to such movement. Projecting upward from the rock-shaft is an arm 116 with which the corresponding shoe on the train is adapted to 40 contact. Also mounted upon the rock-shaft is a relatively short arm 117 lying in the plane of a knife switch, this arm being adapted when the rock-shaft is turned in the direction of the arrow in Fig. 8, to 45 engage between or with the contact springs 118. Now if these contact springs 118 be grounded and the arm is turned over so as to bring the contact member 117 into electrical engagement with the springs 118 it is 50 obvious that electrical engagement will be made between the ground and the shoe engaging the arm 116.

In Fig. 10 I have illustrated the arrangement of track contacts in connection with 55 a block A' for signaling the conditions in blocks A', B' and C'. As there shown, a battery *a* is bridged across the rails of each block adjacent one end and the track contacts A, B, C and D are disposed adjacent 60 the other end of the block. A wire *b* permanently grounds the test track contact A to one of the rails, while a wire *c* leads from the track contact B to a point *d* of a two-point relay *e* which is bridged across the 65 rails of the next adjacent track. When this

magnet is energized, the point *d* contacts with a wire *f* leading to a ground, while when it is deenergized its second point *g* contacts with a wire *h* leading to the ground. A wire *i* leads from the point *g* to the contact D which is the danger contact, B being the clear contact. A relay *j* is bridged across the rails of the block C' and its point *k* is connected by a wire *l* to the contact C. This point in deenergized position 75 of the relay, contacts with a wire *m* leading to the ground, the contact C being the caution contact.

It is not believed necessary to recapitulate the operation of the invention as it is 80 believed that it will be fully understood from what has gone before, but attention is again directed to the fact that with my mechanism the engineer receives three signals, viz., a clear signal, a cautionary signal, 85 and a danger signal so that he knows exactly the condition of the track ahead. Furthermore, unless the train is running at a speed not greater than the speed it should run then after having received a cautionary 90 signal or a danger signal the speed of the train will be reduced until it is within the proper limit and with this reduction in the speed of the train, caused by the application of the brakes the engineer has nothing to 95 do. It is automatic in its action and the engineer cannot prevent the application of the brakes. Furthermore, the engineer cannot release the brakes so long as the train continues to run at a speed greater than it 100 should under a cautionary or a danger signal.

Furthermore, if on a perfectly clear track the engineer attempts to run his train faster than a certain predetermined maximum speed the brakes will be automatically set and the speed reduced to the proper degree.

It will be obvious that my invention does not in any way prevent the application of the brakes by the engineer himself, nor in 110 any way affect the proper control of the train by the engineer.

While I have described the cautionary contacts as being disposed at the entrance of a block, it is preferable that the cautionary contacts will be disposed at the middle of the block. Whenever it is desirable to reduce the speed of a train, as for instance, at the beginning of a dangerous curve or at the entrance of a bridge or in running 120 through a town, it is entirely possible to place a cautionary switch or a danger track contact switch permanently grounded which will cause the actuation of the brakes to reduce the speed of the train either to a speed 125 not greater than twenty miles an hour, for instance, or a speed not greater than five miles an hour, for instance. It will be seen that my invention eliminates all possibility of the engineer "taking chances" and push- 130

ing his train at a high rate of speed in order to make up time. If there is any failure in this system the mechanism will be shifted to a danger position and brakes applied to bring the train to a speed of less than five miles an hour. This will automatically prevent the engineer from running the train at a high rate of speed until he can repair the damaged connection or reach a station where he can secure a key whereby to unlock the casing surrounding the air-valve, for instance, and thus close the air valve, even though the magnets 32 be deenergized. After that, of course, the train will run in the ordinary manner, but it is obvious that the engineer will have to report for instance for cutting out the automatic mechanism to the station agent from whom he procures the key and that he will have to run on telegraphic orders from there on to his destination unless he meanwhile repairs his damaged mechanism.

This present system does not in any way prevent the use of semaphore signals, such as are now used on block systems, but it does away with the necessity of these semaphore signals, as the engineer receives these same signals in the cab of the engine.

By the terms "vehicle" and "train," as employed in the claims, I intend to indicate any vehicle or connected vehicles adapted to travel upon track rails, such as a locomotive, a locomotive and its tender or what is commonly known as a train including a locomotive, tender and one or more cars.

Having thus described the invention what is claimed as new is:—

1. In a vehicle, the combination with a brake applying means, of a maximum, a minimum and an intermediate speed governed means for automatically actuating the brake applying means to apply the brake on an increase of the vehicle speed beyond a maximum, a minimum or an intermediate speed, respectively, and means governed by the position of another vehicle for automatically rendering any one of the speed-governed means active.

2. In a vehicle, the combination with a brake applying means, of a minimum, a maximum and an intermediate speed governed means for automatically actuating the brake applying means to apply the brake, on an increase of vehicle speed beyond a maximum, a minimum or intermediate speed, respectively, one of said means when in operation rendering the others of said means inactive, and means governed by the position of another vehicle for rendering any one of said speed governed means active.

3. In a vehicle, the combination with a brake applying means, of a plurality of speed governed brake applying circuits, each controlling the brake applying means at different vehicle speeds, each when active

placing the other speed governed circuits out of operation, each circuit operating to apply the brake, when the vehicle speed is greater than a predetermined speed, and means governed by the position of another vehicle for rendering any one of said speed governed circuits active.

4. In a vehicle, the combination with a brake applying means, of a plurality of speed governed brake applying circuits, each controlling the brake applying means at different vehicle speeds, each when active placing the other speed governed circuits out of operation, each circuit operating to apply the brake when the vehicle speed is greater than a predetermined speed, and means controlled by the position of another vehicle on the same track for automatically rendering any one of the said speed governed circuits active.

5. In a vehicle, the combination with a brake applying device, of a plurality of means for automatically actuating the brake applying device to apply the brake to be operated in different circumstances, maximum, minimum and intermediate speed governed means for automatically actuating the brake applying device to apply the brake, the minimum and intermediate speed governed means being placed in condition for operation upon the actuation of a corresponding first-named means, and each operating to apply the brake if the speed of the vehicle is greater than the minimum or intermediate speeds, respectively, the maximum speed governed means acting to actuate the brake applying device to apply the brake if the speed of the vehicle is greater than the maximum, and manually operable means for actuating the brake applying device to release the brake after such an automatic application if the speed is below intermediate or minimum limit.

6. In a vehicle, the combination with a brake applying device, of a plurality of means for automatically actuating the device to apply the brake, the minimum and intermediate speed governed means being placed in condition for operation upon the actuation of the corresponding first-named means and each operating to actuate the brake applying device to apply the brake if the speed of the vehicle is greater than the minimum or intermediate speeds, respectively, the maximum speed governed means operating to actuate the brake applying device to apply the brake if the speed of the vehicle is greater than a maximum speed, means for rendering any one of said speed governed means active and coincidentally rendering the other speed governed means in-

active, and manually operable means for actuating the brake applying device to release the brake after such automatic application if the speed of the vehicle is below the 5 intermediate or the minimum limit.

7. In a cab signal system, the combination with a vehicle and a brake applying device, of a plurality of different signal devices, independent track controlled circuits for actuating 10 each of said signal devices, means for actuating the brake applying device to apply the brake upon the actuation of certain signal devices, and means for actuating the brake applying device to release the brake 15 provided the speed of the vehicle is within a certain predetermined limit.

8. In a cab signal system, the combination with a vehicle and a brake applying device, of a track controlled clear signal, a 20 track controlled cautionary signal, a circuit for actuating the brake applying device to apply the brake upon the receipt of said cautionary signal, and means for actuating the brake applying device to release the brake 25 provided the vehicle is moving at a speed less than a predetermined speed.

9. In a cab signal system, the combination with a vehicle and a brake applying device, of a track controlled clear signal, a track 30 controlled cautionary signal, a track controlled danger signal, circuits for actuating the brake applying device to apply the brake upon the receipt of either the cautionary signal or the danger signal, and 35 manually operated means for actuating the brake applying device to release the brake, when so applied, provided the vehicle is moving at speeds less than predetermined speeds.

40 10. In a cab signal system, the combination with a vehicle and a brake controlling means, of a track controlled clear signal, a track controlled cautionary signal, a track 45 controlled danger signal, means for actuating the brake controlling means to apply the brake upon a movement of the vehicle under a clear signal at a speed greater than a predetermined speed, means for actuating the brake controlling means to apply the 50 brake upon the receipt of a cautionary signal, means for actuating the brake controlling means to release the brake after the receipt of a cautionary signal provided the vehicle is moving at a speed less than a predetermined speed, means for actuating the 55 brake controlling means to apply the brake on the receipt of a danger signal, and means for actuating the brake controlling means to release the brake after the receipt of a danger signal providing the vehicle is moving at a speed less than a predetermined speed.

60 11. In a block signal system, a track, a clear signal track contact mounted thereby and adapted to be grounded by the absence

of a train in proximity thereto, a cautionary 65 track contact adapted to be grounded by the presence of a train within a predetermined distance thereof, and a danger signal track contact adapted to be grounded by the presence of a train in proximity 70 thereto, of a vehicle, a clear signal, a cautionary signal and a danger signal, a clear shoe, a cautionary shoe and a danger shoe adapted to engage respectively with the clear, cautionary and danger track contacts, means actuated by the engagement of the clear shoe with the clear track contact when grounded, for actuating the clear signal, means actuated by the engagement of the cautionary shoe with the cautionary 75 track contact when grounded, for rendering the clear signal inactive and for rendering the cautionary signal active, and means actuated by the engagement of the danger shoe with the danger track contact when 80 grounded, for actuating the danger signal and for rendering the cautionary and clear signals inactive.

12. In a block signal, the combination with a track having clear, cautionary and danger contacts mounted thereby, and means for grounding the clear contact upon the absence of a train within a predetermined distance thereof, and for grounding the cautionary and danger contacts upon 90 the presence of a train on the track ahead within predetermined distances thereof, of a vehicle having clear, cautionary and danger contact shoes adapted to engage the track contacts, a brake controlling means, 95 means for actuating the brake controlling means to apply the brake, upon the engagement of either the cautionary or danger shoe with its respective track contact when grounded, and means for actuating the 100 brake controlling means to release the brake if previously applied upon the engagement of the clear shoe with the clear track contact when grounded.

13. In a block signal system, the combination with a track, having thereby clear, cautionary and danger track contacts, and means for grounding the clear contact upon the absence of a train on the track ahead for a predetermined distance and for 110 grounding the cautionary and danger track contacts, respectively, upon the presence of a train on the track ahead within certain predetermined distances of a vehicle, clear, 115 cautionary and danger contact shoes carried upon the vehicle and engageable, respectively, each with a track contact, clear, cautionary and danger signals, electrically actuated brake applying means, means actuated by engagement of the clear shoe with the clear track contact for operating the clear signal, and actuating the brake applying means to release the brake if previously 120 125

- applied, means for operating the cautionary signal and rendering inoperative the clear signal upon the engagement of the cautionary shoe with the cautionary track contact if grounded, and for coincidentally actuating the brake applying means to apply the brake, and means acting upon the engagement of the danger shoe with the danger track contact, if grounded, to operate the danger signal and to render inoperative the cautionary and clear signals and to apply the brakes.
14. In a block signal system, the combination with a track, divided into blocks, of a vehicle moving on the track, brake controlling means on the vehicle, a plurality of signal devices carried on the vehicle, means actuated at the beginning of a block, for causing the deenergizing of all of said signal devices and the application of the brake by the brake controlling means if no other signal is immediately received, and means for actuating one of said signal devices and releasing said brake by the brake controlling means if the block ahead is clear, or for actuating another of said signaling devices and for holding the brake applied by the brake controlling means if there is a train on the track ahead within a predetermined distance.
15. In a block signal system, a track divided into blocks, a vehicle operating thereon, a source of electrical energy mounted on the vehicle, danger, cautionary and clear signals, each disposed in a circuit with the source of energy brake controlling means, means actuated by the arrival of a train at a predetermined point in the block for breaking the circuit through the several signals and momentarily actuating the brake controlling means to apply the brake, and subsequently acting means for completing a circuit through either the clear, cautionary or danger signals, said means acting to hold the brake applied by the brake controlling means on a completion of the circuit through either the cautionary or the danger signals but to release the brake by the brake controlling means upon the completion of the circuit through the clear signal.
16. In a block signal system, a track divided into blocks, a vehicle, electrically operated brake controlling means and a source of electrical energy thereon, a danger signal, a cautionary signal and a clear signal each disposed in a circuit with the source of energy, and means actuated by the arrival of the vehicle at a predetermined point in the block, for breaking a circuit through the several signals and for actuating the brake controlling means to momentarily apply the brake and subsequently acting means for completing a circuit through the clear signal and for actuating the brake controlling means to release the brake or for completing a circuit either through the cautionary or the danger signals and for continuing the application of the brakes by the brake controlling means upon the completion of the circuit through either the cautionary or danger signals.
17. In a block signal system, a track divided into blocks, a permanently grounded test contact near the track, a clear contact adapted to be grounded by the absence of a train on the track ahead within a predetermined distance, a cautionary contact adapted to be grounded by the presence of a train on the track ahead within a certain predetermined distance, and a danger contact adapted to be grounded by the presence of a train on the track ahead within a certain other predetermined distance, a vehicle operated on the track, a source of electrical energy thereon, a clear signal, a cautionary signal, and a danger signal, each disposed in a circuit with the source of energy, electrically actuated brake controlling means disposed in a circuit with the generator, and means actuated by the arrival of the vehicle at the test contact for breaking the circuit through the several signals and the circuit through the brake controlling means to thereby momentarily apply the brake, and subsequently acting means engaging the clear, cautionary or danger contacts and acting when one or the other of these contacts is grounded to complete a circuit through either the clear, cautionary or danger signals, the completion of the circuit through the danger or cautionary signals acting to break the circuit through the brake controlling means and thereby apply the brakes.
18. In a block signal system, a track divided into blocks, a test contact, a clear contact, a cautionary contact and a danger contact disposed near said track, the test contact being permanently grounded, a vehicle traveling on the track, a source of electrical energy thereon, a test, clear, cautionary and danger shoes adapted to respectively engage with the test, clear, cautionary and danger contacts, clear, cautionary and danger signals, electrically operated brake controlling means normally connected in circuit with the source of energy, means actuated upon an electrical engagement of the test shoe with the test contact for breaking any circuit through the signals, and the circuit through the brake controlling apparatus, to the generator, means actuated by a subsequent contact with the clear signal shoe for establishing a circuit through the brake controlling apparatus and through the clear signal, means acting upon a con-

tact of the cautionary shoe with the cautionary contact for establishing a circuit through the cautionary contact and for breaking the circuit through the clear signal and also for breaking the circuit through the brake-controlling apparatus to cause an application of the brakes, and means actuated by engagement of the danger shoe with the danger contact for breaking the circuits through the clear signal and through the brake-controlling apparatus to thereby apply the brakes and for establishing a circuit through the danger signal.

19. In a block signal system, a track divided into blocks, a test contact, a clear contact, a cautionary contact and a danger contact disposed near said track, the test contact being permanently grounded, a vehicle traveling on the track, a source of electrical energy thereon, test, clear, cautionary and danger shoes adapted to respectively engage with the test, clear, cautionary and danger contacts, clear, cautionary and danger signals, electrically operated brake controlling means normally connected in circuit with the source of energy, means actuated upon an electrical engagement of the test shoe with the test contact for breaking any circuits through the signals and through the 25 brake controlling apparatus and means actuated by a subsequent contact with the clear signal shoe for establishing a circuit through the brake controlling apparatus and through the clear signal, means acting 30 upon a contact of the cautionary shoe with the cautionary contact for completing a circuit through the cautionary contact and for breaking the circuit through the clear signal and also for breaking the circuit through the 35 brake-controlling apparatus to cause an application of the brakes, means actuated by engagement of the danger shoe with the danger contact for breaking the circuits through the clear signal and through the 40 brake controlling apparatus to thereby apply the brakes and for establishing a circuit through the danger signal, and speed controlled means for breaking the circuit through the 45 brake controlling apparatus to thereby apply the brakes and for establishing a circuit through the danger signal, and speed controlled means for breaking the circuit through the 50 brake controlling apparatus to thereby apply the brakes and for establishing a circuit through the danger signal, and speed controlled means for breaking the circuit through the danger signal and also for establishing a circuit through the 55 brake controlling apparatus normally connected in circuit with the source of energy, means actuated upon an increase in speed of the vehicle above a predetermined point.

20. In a block signal system, a track divided into blocks, a test contact, a clear contact, a cautionary contact and a danger contact disposed near said track, the test contact being permanently grounded, a vehicle traveling on the track, a source of electrical energy thereon, test, clear, cautionary and danger shoes adapted to respectively engage with the test, clear, cautionary and danger contacts, clear, cautionary and danger signals, an electrically operated brake controlling apparatus normally con-

nected in circuit with the source of energy, means actuated upon an electrical engagement of the test shoe with the test contact for breaking any circuits through the signals and through the brake controlling apparatus and generator, means actuated by a subsequent contact with the clear signal shoe by a clear contact for establishing a circuit through the brake controlling apparatus and through the clear signal, means acting upon a contact of the cautionary shoe with the cautionary contact for completing a circuit through the cautionary contact and for breaking the circuit through the clear signal and also for breaking the circuit through the brake-controlling apparatus to cause an application of the brakes, means actuated by engagement of the danger shoe with the danger contact acting to break the circuit through the clear signal and through the brake controlling apparatus to thereby apply the brakes and also acting to establish a circuit through the danger signal, a plurality of means corresponding to the clear, cautionary, and danger signals, acting to break the circuit from the generator through the brake controlling apparatus each upon increases in speed of the vehicle beyond predetermined points.

21. In a mechanism of the character described, a vehicle having test, clear, cautionary, and danger shoes adapted to be grounded by engagement with test, clear, cautionary and danger track contacts respectively, a source of electrical energy carried upon the vehicle, danger, cautionary and clear signals also carried by the vehicle, an electrically operated brake controlling valve mechanism normally held in a closed position, and means for establishing or disestablishing electrical connection between the source of energy and the several signals and the valve actuating mechanism, said means including a pair of independently operable slides one connected to the source of energy, and the other shiftable into a position to close a circuit from the source of energy through the clear signal or into a position to close a circuit through the cautionary signal, the first-named slide being also shiftable into a position to break the circuit to the second named slide and close the circuit through the danger signal, and means, operating upon movement of the slides to close a circuit through the danger or the cautionary signal, to open said valve mechanism.

22. In a cab signal system, a vehicle, clear, cautionary and danger signals on the vehicle, an air brake controlling valve, an electromagnet normally holding the valve closed, a generator connected in a normally closed circuit with the magnet, and means

operating upon an actuation of the danger or cautionary signal for deenergizing said magnet and opening the valve.

23. In a cab signal system, a vehicle, clear, cautionary and danger signals on the vehicle, a brake controlling valve, an electromagnet when energized holding the valve closed, a source of electrical energy connected in a normally closed circuit with the magnet, track contact controlling signal circuits operating upon an actuation of the danger or the cautionary signal for deenergizing said magnet and opening the valve, to thereby apply the brakes, a circuit closer in the said closed circuit, a normally energized magnet normally holding the circuit closer closed, speed governed means for breaking the circuit through said magnet when the speed of the vehicle is greater than a predetermined speed and the circuit through the clear signal is closed and for breaking said circuit through the magnet when the speed is greater than a predetermined speed and the cautionary signal circuit is closed and for breaking the circuit through said magnet when the speed is greater than a predetermined speed and the circuit through the danger signal is closed.
24. In a cab signal system, a vehicle, clear, cautionary and danger signals upon the vehicle, a brake controlling valve, a normally closed circuit holding the valve closed, source of electrical energy in the normally closed circuit, track contact controlled circuits operating upon an actuation of the danger and cautionary signal for deenergizing the circuit to open the valve and thereby apply the brakes, a circuit closer in the said closed circuit, a normally energized magnet normally holding the circuit closer closed, speed governed means for breaking the circuit through said magnet when the speed of the vehicle is greater than a predetermined speed and the circuit through the clear signal is closed and for breaking said circuit through the magnet when the speed is greater than a predetermined speed and the cautionary signal circuit is closed and for breaking the circuit through said magnet when the speed is greater than a predetermined speed and the circuit through the danger signal is closed, said means including a speed governor actuated member and a plurality of circuit breaking elements adapted to be successively engaged by said member to break their circuits upon increases of vehicle speed of said elements each being disposed in a circuit with the source of energy and its respective signal circuit whereby each element is active when its signal circuit is active.
25. In a cab signal system, a vehicle, clear, cautionary and danger signals upon the

vehicle, clear, cautionary and danger signal circuits, a source of electrical energy common to all of said circuits, means upon the vehicle co-operating with track contacts for grounding any one of said circuits to thereby energize one or the other of the signals, a brake controlling magnet normally energized when the clear signal is energized and holding the brakes from application, means operated by the grounding of the danger signal or cautionary signal circuits acting to deenergize said magnet to thereby cause an application of the brakes, circuit closures arranged in three several circuits with said magnet and movable independently, the circuit closers corresponding to the clear, cautionary and danger signals, and each being rendered active by the grounding of its corresponding signal circuit, and speed controlled means for successively breaking the circuits through the several circuit closers when the speed of the engine increases.

26. In a cab signal system, a vehicle, clear, cautionary and danger signals on the vehicle, a brake controlling valve, an electromagnet normally holding the valve closed, a source of electrical energy in a normally closed circuit with the magnet, and means operating upon an operation of the danger or cautionary signals for deenergizing said magnet to open the valve and apply the brakes, said means including a slide normally connected in circuit with the source of energy, the slide in one position being electrically connected with the clear signal and in another position electrically connected with the cautionary signal to thereby close either circuit a second slide, the first-named slide in one position connecting the second-named slide with the source of energy and in the other position breaking said connection, means normally urging the first-named slide into position to connect the second-named slide with the source of energy, means urging the second-named slide into position to close the circuit to the clear signal, track controlled means for shifting the second-named slide into position to close the circuit through the cautionary signal and break the circuit through the clear signal, track controlled means for shifting the first-named slide into position to break connection with the second-named slide and to establish connection between the danger signal and the source of energy, means for holding the slides in their shifted positions, and track controlled means for releasing the slides.

27. In a cab signal system, clear, danger, and cautionary signals, a generator, separate circuits connecting each of said signals to the generator, track controlled means for breaking or closing a circuit through

- any one of said signals and for closing or opening circuits through the other signals, brake actuating means electrically disconnected from the generator upon the establishment of a circuit through either the danger or the cautionary signal, a pair of normally energized high resistance magnets, disposed in the cautionary and danger circuits, and circuit closers controlled by said magnets disposed in a circuit leading from the generator to all of said signals and to the brake actuating mechanism for rendering all of said signals inactive and for applying the brakes upon the deenergizing of said magnets.
28. In a block signal system, the combination with a track divided into blocks, of a vehicle movable upon the track, brake applying means upon the vehicle, a plurality of speed governed means operable upon changes in vehicle speed to actuate the brake applying means to apply the brake, and means controlled by the position of other trains upon the track determining which of the speed governed means shall be active.
29. In a vehicle, the combination with a track divided into blocks, a vehicle movable upon the track, a brake applying means upon the vehicle, of maximum, minimum and intermediate speed governed means for automatically actuating the brake applying means to apply the brake on an increase of vehicle speed beyond a maximum, a minimum or an intermediate speed, respectively, means whereby when any one of the speed governed means is active the others are rendered inactive and means controlled by the position of other trains upon the track determining which of the speed governed means shall be active.
30. In a vehicle, the combination with a brake applying device, of a plurality of means for automatically actuating the brake applying device to apply the brake and adapted to be operated under different circumstances, maximum, minimum and intermediate speed governed means for automatically actuating the brake applying device to apply the brake, the minimum and intermediate speed governed means being placed in condition for operation upon the actuation of the corresponding first named means and the maximum speed governed means acting to actuate the brake applying device to apply the brake if the speed of the vehicle is greater than the maximum.
31. In a cab signal system, the combination with a vehicle and a brake applying device, of a track controlled clear signal, a track controlled cautionary signal, a circuit for actuating the brake applying device to apply the brake upon the receipt of said cautionary signal, and manually operable means for actuating the brake applying device to release the brake providing the vehicle is moving at a speed less than a predetermined speed.
32. In a block signal system, a track, clear, cautionary and danger track contacts disposed adjacent the track, a vehicle operating on the track, clear, caution and danger shoes on the vehicle, clear, caution and danger signals controlled by engagement of their respective shoes with corresponding track contacts, and means whereby when any signal is active the other signals are rendered inactive.
33. In a block signal system, the combination with a track divided into blocks, of a vehicle moving on the track, a brake controlling means on the vehicle, a plurality of signal devices on the vehicle, means actuated at the beginning of a block for rendering inactive all of the signal devices and for actuating the brake controlling means to apply the brake unless a signal proper to the condition of the track is received, and means actuated adjacent the entrance of a block for giving a signal proper to the condition of the block.
34. In a cab signal system, a vehicle, clear, cautionary and danger signals on the vehicle, an air brake controlling valve thereon, means normally holding the valve closed including a normally closed energized circuit, and means operating upon an actuation of the danger or cautionary signal for rendering such valve holding means inoperative to permit opening of the valve.
35. A cab signal system including a normally closed brake controlling circuit, a circuit breaker in said circuit, a normally closed circuit adapted to be shorted by a track contact and controlling the circuit breaker, a plurality of main track contact controlled circuits normally closed, normally closed circuit breakers controlled one by each of said main circuits, each being adapted to open upon a shorting of its main circuit and each operable to open the brake circuit, and independent track controlled means for shortening the main circuits.
36. In a block signal system, the combination with a track divided into blocks, of train carried means including a test contact shoe in a normally closed circuit for giving a test indication at the entrance of each block, and means including additional contact shoes for giving an additional signal of the proper character immediately after receipt of the test indication.
37. In a block signal system, the combination with a track divided into blocks, of clear, caution and danger signals, a vehicle movable on the track, brake controlling means mounted upon the vehicle, a test con-

tact shoe in a normally closed circuit engageable with a contact disposed adjacent the entrance of a block to give a test indication and also actuate the brake controlling means unless another signal proper to the condition of the block is received, and means including additional contact shoes engageable with contacts disposed adjacent the entrance of the block for subsequently giving an additional signal of the proper character after the receipt of the test indication.

38. In a block signal system, the combination with a track divided into blocks, of clear, caution and danger signals, a vehicle movable on the track, brake controlling means mounted upon the vehicle, a test contact shoe in a normally closed circuit engageable with a contact disposed adjacent the entrance of a block to give a test indication and actuate the brake controlling means unless another signal proper to the condition of the block is received, means including additional contact shoes engageable with contacts disposed adjacent the entrance of the block for subsequently giving an additional signal of the proper character after the receipt of the test indication, and manually operable means for actuating the brake controlling means to release the brake after receipt of a test indication if no other signal follows.

39. In a block signal system, the combination with a vehicle and a brake controlling mechanism, of clear, caution and danger signals, a track controlled test indicating circuit adapted to actuate the brake controlling mechanism, to apply the brake no further signal is received, a track controlled clear signal circuit adapted to actuate the brake controlling mechanism to release the brake after a test indication has been received, and track controlled caution and danger signal circuits adapted to actuate the brake controlling mechanism to prevent release of the brake after receipt of a test indication.

40. In a block signal system, the combination with a vehicle and a brake controlling mechanism, of clear, caution and danger signals, a track controlled test indicating circuit adapted to actuate the brake controlling mechanism to apply the brake if no other signal is received, a track controlled signal circuit adapted to actuate the brake controlling mechanism to release the brake after a test indication has been received, track controlled caution and danger signal circuits adapted to actuate the brake controlling mechanism to prevent release of the brake after receipt of a test indication, manually operated means for actuating the brake controlling mechanism to release the brake after receipt of a caution or danger signal.

41. In a block signal system, the combination with a vehicle and a brake controlling mechanism, of clear, caution and danger signals, a track controlled test indicating circuit adapted to actuate the brake controlling mechanism to apply the brake if no further signal is received, a track controlled clear signal circuit adapted to actuate the brake controlling mechanism to release the brake after a test indication has been received, track controlled caution and danger signal circuits adapted to actuate the brake controlling mechanism to prevent release of the brake after receipt of a test indication, and means controlling the speed of the vehicle under any signal.

42. In a block signal system, the combination with a vehicle and a brake controlling mechanism, of clear, caution and danger signals, a track controlled test indicating circuit adapted to actuate the brake controlling mechanism to apply the brake if no further signal is received, a track controlled clear signal circuit adapted to actuate the brake controlling mechanism to release the brake after a test indication has been received, track controlled caution and danger signal circuits adapted to actuate the brake controlling mechanism to prevent release of the brake after receipt of a test indication, manually operated means for actuating the brake controlling mechanism to release the brake after receipt of a caution or danger signal, and means controlling the speed of the vehicle under any signal.

43. In a block signal system, the combination with a vehicle and an electrically operated brake controlling mechanism adapted when energized to hold the brakes in released position, of a normally closed circuit for such mechanism, a circuit breaker in said circuit, a multi-branched circuit controlling the circuit breaker, but one branch of said circuit being active at any one time, and means in each branch of the circuit controlling the speed at which the vehicle may travel when said branch of the circuit is active.

44. In a block signal system, the combination with a vehicle and an electrically operated brake controlling mechanism adapted when energized to hold the brakes in released position, of a normally closed circuit for such mechanism, a circuit breaker in said circuit, a multi-branched circuit controlling the circuit breaker, but one branch of said circuit being active at any one time, means in each branch of the circuit controlling the speed at which the vehicle may travel when said branch of the circuit is active, and block condition controlled means determining which branch shall be active.

45. In a block signal system, the combination with a vehicle, of a brake actuating

mechanism, a track controlled test indicating circuit, clear, caution and danger signals, means operable upon receipt of a test indication for actuating the brake applying mechanism to apply the brake if a further signal is not received, means including clear, caution and danger circuits for giving further signals, and a multiple speed governed circuit breaker common to all of

said latter circuits and controlling the brake actuating mechanism.

In testimony whereof I affix my signature in presence of two witnesses.

MARSENA R. JULIAN. [L. S.]
